(57) **CLAIM**

The ornamental design for a steamer attachment, as shown and described.

DESCRIPTION

FIG. 1 is a perspective view of a steamer attachment showing my new design;

FIG. 2 is a first side elevational view of the steamer attachment;

FIG. 3 is a second side elevational view of the steamer attachment;

FIG. 4 is a front elevational view of the steamer attachment; FIG. 5 is a rear elevational view of the steamer attachment; FIG. 6 is a top plan view of the steamer attachment; and, FIG. 7 is a bottom plan view of the steamer attachment.

In the drawings, the broken lines in FIGS. 1-5 and 7 depict portions of the design that form no part of the claim.
